ENDLESS LOOP TYPE CUTTER CHAIN

Joseph F. Joy, Pittsburgh, Pa., assignor to Joy Manufacturing Company, Pittsburgh, Pa., a corporation of Pennsylvania

Application March 24, 1951, Serial No. 217,332

7 Claims. (Cl. 262—29)

This invention relates to cutter chains, and more particularly to an endless loop type cutter chain for cutting a kerf in an upright orbital path in the mineral of a mine vein to form a core of material to be dislodged.

In endless loop type cutter chains of known types the chain is usually guided for orbital circulation about the margin of an open-centered guide frame whereby a core of mineral may be cut from a solid mine vein, with the core extending freely into the open center of the guide frame in such position as to be dislodged in fragments from the solid vein as cutting progresses. In such cutter chains great difficulty has been encountered due to space restrictions in obtaining the desired ruggedness and simplicity in design so as to enable the chain to stand up under the relatively severe conditions of service. The present invention contemplates improvements over known types of loop cutter chains in that not only is ruggedness and simplicity in design, but also compactness, are obtained, resulting in a cutter chain well adapted for its intended purpose.

A primary object of the present invention is accordingly to provide an endless loop type cutter chain which is simple, rugged and compact in design. Another object is to provide an improved endless cutter chain having an improved construction and arrangement of the chain elements and their cooperating guiding means whereby the inherent weaknesses of known types of chains are to a large extent, overcome. These and other objects and advantages of the invention will, however, hereinafter more fully appear in the course of the ensuing description.

This application is a continuation in part of my copending application, Serial No. 194,259, filed November 6, 1950.

In the accompanying drawing there are shown for purposes of illustration two forms which the invention may assume in practice.

In this drawing:

Fig. 1 is a fragmentary plan view, with parts in horizontal section, illustrating a loop type cutter chain constructed in accordance with a preferred illustrative embodiment of the invention.

Fig. 2 is a fragmentary view in front elevation of the cutter chain shown in Fig. 1.

Fig. 3 is a cross section taken on line 3—3 of Fig. 1 and showing a portion of the associated guide frame.

Fig. 4 is a perspective view of one of the chain elements of the preferred embodiment.

Fig. 5 is a view similar to Fig. 1 showing a modified form of construction.

Fig. 6 is a fragmentary front elevational view of the chain shown in Fig. 5.

Fig. 7 is a cross section taken on line 7—7 of Fig. 5 and showing a portion of the associated guide frame.

Fig. 8 is a perspective view of one of the chain link elements of the modified embodiment.

In both illustrative embodiments of the invention, the

2

improved cutter chain is of the endless loop type and is associated with a generally rectangular, open-centered guide frame or guide bar as is fully disclosed in my copending application, Serial No. 194,259 above referred to, or as is disclosed in my copending application, Serial No. 214,242, filed March 7, 1951, which has since issued as Patent No. 2,730,346. Evidently, various features of the invention may be embodied in cutter chains of other types.

10 In the illustrative construction shown in Figs. 1 to 4 inclusive, an endless loop type cutter chain generally designated 1 is guided for orbital circulation about the margin of a guide frame generally designated 2. The rectangular, open-centered guide frame includes a guide member 3 supported by a suitable frame structure 4 and having a guideway 5 extending about its margin and opening forwardly through the forward side of the guide member. The guideway is of generally T-shape in cross section and includes opposed rectangular guide channels 6 provided at the head of the T and parallel plane side guiding surfaces 7 disposed at the leg of the T, as clearly shown in Fig. 3. The endless loop cutter, which travels in a rectangular orbital path about the guide frame, is in the form of a pivoted link chain comprising a series of 15 cutter blocks 8 pivotally connected by intermediate strap links 9. As shown most clearly in Fig. 1, the chain blocks each comprises an outer or front plate 10 and an inner or rear plate 11, the plates arranged in parallel relation, and the inner plate having parallel horizontal hinge pins 12 formed integral therewith. The strap links 9 pivotally engage these hinge pins at 13 intermediate the parallel plates. The hinge pins extend forwardly from the rear plates and have reduced forward end portions 14 which provide forwardly facing shoulders 15 with which the rear 20 surfaces 16 of the outer plates 10 abut, so that the hinge pins fixedly space the inner and outer plates of each block. The reduced end portions of the hinge pins are threaded at 17 and nuts 18 engage the threads of these reduced pin portions to hold the plates of each block in 25 rigid spaced relation with the intermediate strap links pivotally engaging the enlarged intermediate portions of the pins. The outer plates 10 have lateral socketed lugs 19 in which cutter bits or teeth 19' are mounted, and this lug and bit structure may be similar to that disclosed 30 in my copending application, Serial No. 57,047, filed October 28, 1948 which has since been abandoned.

In this illustrative embodiment the inner or rear plates 11 of the chain blocks have rearwardly projecting teeth 20 which, as shown most clearly in Fig. 1, are engaged 35 by the teeth 21 of a large spur gear or rotary toothed element 22, in the manner fully disclosed in my copending application, Serial No. 194,259 mentioned above. This rotary toothed member projects forwardly within a horizontal recess 23 in the guide frame so that the teeth 20 thereof may have driving engagement with the teeth 20 on the endless chain. The bit or tooth supporting lugs 19 are disposed in different angular positions on the front plates 10, and some of the lugs are double while others are single, and by so arranging the lugs, the bits on the 40 different blocks are staggered or laced in such manner that they may cut a kerf in the mine vein of sufficient width to receive the guide frame.

As shown in Fig. 3, the side flanges 24 of the rear plates 11 of the blocks slidably engage the guide channels 6, 45 the sides of the strap links 9 slidably engage the guiding surfaces 7 and the flanges 25 of the front plates 10 overlie and ride against the front surface of the guide frame. The teeth 20 on the rear plates 11 of the block project rearwardly into the recess 23 into engagement with the teeth 20 of the drive gear.

In the modified construction shown in Figs. 5 to 8

inclusive, the cutter chain comprises a series of chain blocks 26 pivotally connected by intermediate strap links 27. Each chain block comprises an inner or rear plate 28 and a front or outer plate 29, the plates arranged in parallel relation and the front plate having parallel horizontal hinge pins 30 integral therewith and with which the strap links pivotally engage. The hinge pins project rearwardly from the front plates and have rearward reduced portions 31 providing inwardly facing shoulders 32 with which the rear plates abut for fixedly spacing the inner and outer plates apart and the reduced portions are threaded at 33 for engagement with nuts 34 for rigidly securing the inner and outer plates in spaced relation. The intermediate strap links 27 pivotally engage the enlarged intermediate portions of the pins, as shown in Fig. 5. The strap links have circular portions 35 extending between parallel front and rear link portions 36 and 37 and separated by spaces 38 which are adapted to receive the teeth of a drive sprocket 39 shown in broken lines in Fig. 6, and the sprocket teeth drivingly engage the rear surfaces of the circular link portions 35 to drive the cutter chain. The outer plates 29 have lateral lugs 40 which have sockets 41 for receiving the double-ended, reversible cutter bits or teeth 42. These cutter bits have angularly disposed cutting portions 43 and the inactive cutting portions are received in the sockets 41 with the active cutting portions projecting outwardly and forwardly inclined, as shown in Fig. 5. The bits have rear lugs 44 which rest on the outer surfaces of the lugs 40 to limit the projection of the bit within the lug sockets thereby to provide a predetermined bit gauge. Threaded within the forward portions of the lugs are conventional set screws 45 which engage the inactive cutting portions of the bits for firmly securing the bits in position on the lugs. Each of the cutting portions of the bit may be provided with a hard metal, wear-resisting cutting point 46. This lug and bit structure is fully disclosed in my copending application, Serial No. 57,046, filed October 23, 1948 which has since issued as Patent No. 2,769,628. The bit or tooth supporting lugs 40, as in the preferred embodiment, are arranged in staggered relation on the different blocks to provide for proper lacing of the bits.

The guide frame about which the cutter chain travels in a rectangular orbital path comprises, as shown in Fig. 7, parallel plates 47 separated by spacing elements 48 and held in rigid assembled relation as by rivets 49, and these plates and spacing elements cooperate to provide a guideway 50 of generally T-shape in cross section. This guideway has parallel channels 51 at the head of the T and parallel plane sidewalls 52 disposed at the leg of the T. Extending longitudinally at the inner side or bottom of the guideway is a longitudinal recess 53 in which the projecting threaded portions of the hinge pins and the tightening nuts 34 move during circulation of the chain. The side edges of the rear plates 28 and the flanges 54 of the rear portions 37 of the strap links are guided in the channels 51, and the flanges 55 of the front portions 36 of the strap links overlie and slidably engage the forward face of the guide frame. The flanges of the front plates 29 of the blocks overlie and rest against the front flanges 55 of the strap links, in the manner shown.

In both embodiments of the invention, the rear plates of the blocks are slidably guided within the inner channels of the T-shaped guideway and the outer plates ride against the outer periphery or front face of the guide frame exteriorly of the guideway, so that the chain is firmly supported and guided as it circulates about its guideway on the guide frame. By forming the hinge pins integral with one of the plates of the chain blocks and by firmly clamping the cooperating plates to shoulders on the hinge pins, to hold the plates in rigid spaced relation, an extremely rugged, compact and simple design

is obtained. Other advantages of the invention will be clearly apparent to those skilled in the art.

While there are in this application specifically described two forms which the invention may assume in practice, it will be understood that these forms of the same are shown for purposes of illustration and that the invention may be further modified and embodied in various other forms without departing from its spirit or the scope of the appended claims.

10 What I claim as new and desire to secure by Letters Patent is:

1. In an endless loop type cutter chain of the kind adapted for circulation about an open-centered guide frame, a series of cutter blocks pivotally connected by intermediate strap links, each of said blocks comprising parallel inner and outer plates at least one of which provides a guide portion for the chain and has engagement with the guideway on the guide frame, one of said plates having parallel hinge pins integral therewith and projecting therefrom with the outer end portions of said pins fitted in bores in the other plate, means engaging said outer end portions of said pins and said other plate for securing said plates against lateral separation, and cutter bit supporting lugs integral with one of said plates and projecting from the forward face of the chain, said cutter supporting lugs being so arranged that the cutters cut a slot in a solid mine vein of a width sufficient to receive the guide frame as the latter is advanced toward the face, one of said plates being disposed within the frame guideway and the other plate being disposed exteriorly of the frame-guideway and overlying the outer edge of said guide frame with the cutters projecting outwardly from said frame.

2. A combination as set forth in claim 1 wherein said strap links have inner lateral flanges slidably engaging said guideway and outer lateral flanges overlying and riding against the exterior periphery of said frame exteriorly of said guideway.

3. A combination as set forth in claim 2 wherein said plate which carries a bit supporting lug has flanges overlying and abutting said outer flanges of said strap links.

4. In an endless loop type cutter chain as set forth in claim 1 wherein said strap links each includes inner and outer portions abutting the inner surfaces of said plates and separated by transverse circular hollow portions having bores which receive the hinge pins, said inner link portions having lateral flanges providing guiding surfaces engageable with the guideway of a guide frame and said outer link portions having lateral flanges adapted to overlie and providing guiding surfaces slidably engageable with the guide frame.

5. A combination as set forth in claim 4 wherein said outer plates of said cutter blocks have flanges overlying and resting against the flanges of said outer link portions.

6. A combination as set forth in claim 4 wherein said inner plates of said cutter blocks have lateral flanges disposed inwardly of said flanges of said inner link portions and providing guiding surfaces likewise engageable with the guideway of the guide frame.

7. A combination as set forth in claim 4 wherein said transverse hollow portions of said strap links have spaces therebetween for receiving the teeth of a driving sprocket whereby the sprocket teeth may engage the rear surfaces of said hollow portions to effect driving of the chain.
